JAMES FALLER AND ISAAC LAPIDUS, OF BROOKLYN, NEW YORK.

GUN.

Application filed September 6, 1922. Serial No. 586,488.

To all whom it may concern:

Be it known that we, JAMES FALLER and ISAAC LAPIDUS, citizens of the United States of America, and residents of the city of 5 New York, borough of Brooklyn, in the county of Kings and State of New York, have invented a new and Improved Gun, of which the following is a description.

Our invention relates to firearms and more 10 particularly to a firearm adapted to be gripped with the palm of the hand and carried substantially concealed by the hand with a view to defend one's self against a highwayman whereby if the person carrying the gun 15 is ordered to throw up his hands he will in the act of raising the hands assume a position to discharge the firearm at the highwayman.

The general object of our invention is to 20 provide a gun of the indicated character that may be readily grasped by the hand with the barrel protruding through the fingers and with the trigger disposed for convenient and repeated operation by the 25 thumb of the hand holding the gun.

A further object of the invention is to provide a gun improved in various particulars especially with respect to the means for actuating the firing pin and controlling 30 a revolving magazine so that its radial cartridge chambers will successively be aligned with the gun barrel and maintained in aligned position during the firing.

Reference is to be had to the accompanying 35 drawings forming a part of this specification, it being understood that the drawings are merely illustrative of one example of the invention.

Figure 1 is a perspective view showing a 40 gun embodying our invention held in position ready for firing;

Figure 2 is a section in the plane of the gun;

Figure 3 is a horizontal section on the 45 line 3-3, Figure 2;

Figure 4 is a transverse vertical section on the line 4-4, Figure 2;

Figure 5 is a schematic view of the magazine and firing means.

50 In carrying out our invention in practice in accordance with the illustrated example a casing 10 is provided rounded at its rear end and comparatively within to be held conveniently in the hand at the palm and 55 substantially concealed. One side 11 of the case is hinged or otherwise movably secured.

Said cover is shown as held by a sliding latch 12 having an operating knob 112. A short fixed barrel 13 integral with the case projects forwardly from the straight front 60 end of said case.

A revoluble magazine 14 is provided within the case and formed with radial cartridge chambers 15 in which cartridges are manually placed in the individual chambers. 65 The magazine 14 is formed with a cylindrical bore and is turnably mounted on a fixed cylinder 16 which is secured in position by soldering, brazing, or bolting, or other suitable means, there being indicated 70 a rabbeted head 17 on a bolt 18 secured to said ring projecting through the case and having a nut 19.

A reciprocating trigger 20 is slidably mounted in the case transversely in a plane 75 adjacent to the inner end of the barrel 13 and projects beyond the exterior of the case for convenient operation by the thumb as indicated in Figure 1 when the gun is grasped in the hand.

On the trigger 20 is a fixed plate spring 21 at the interior of the casing, the free end of the spring being deflected laterally to engage that cartridge chamber 15 alining with the barrel 13 so that the magazine 14 will 80 be turned through an arc to bring the next rearward cartridge chamber in line with the barrel. For returning the trigger 20 to the outer position after an inward movement by the thumb we provide a swingable 85 arm 22 pivoted on a stud 24 and in the casing acted upon by an arm of a spring 23 coiled about said stud, the other arm bearing against the interior surface of the casing at a side of the latter.

One cartridge chamber 15 in advance of that engaged by the spring 21 is adapted to engage a flange 25 on a lever 26 pressed by a spring 28 coiled about the fulcrum pin 27 of said lever.

By the described arrangement with the turning of the magazine by the trigger 20 and the spring 21, the lever 26 will be swung and its spring 28 stressed. In the continued movement of the magazine that cartridge 105 chamber 15 engaging the flange 25 will slip by the said flange, thereby releasing the lever 26 and permitting the spring 28 to return the lever to its initial position. The firing pin 29 is rigid on the lever 26 so 110 that upon the rebound of the lever under the action of spring 28 the gun will be dis-

charged. In order to maintain a cartridge chamber in line with the barrel 13 during the rebound of the lever 26 and the firing of the cartridge, we provide a spring stop 31 on the casing at the interior and suitably fastened, there being shown for the purpose of illustration a fastener bolt 32. In the forward turning movement of the magazine 14 under the action of trigger 20 and spring 21, a cartridge chamber 15 will wipe over the spring 31, the latter yielding to the pressure. Upon the barrel passing the free end of the spring, the latter will rebound into the path of the cartridge chamber and prevent the lever 26 or its flange 25 from giving retrograde movement to the magazine.

We would state in conclusion that while the illustrated example constitutes a practical embodiment of our invention, we do not limit ourselves strictly to the exact details herein illustrated, since, manifestly, the same can be considerably varied without departure from the spirit of the invention as defined in the appended claims.

Having thus described our invention, we claim:

1. A gun of the class described including a casing having a cartridge discharge, a revoluble magazine within said casing and provided with radial chambers, a reciprocating trigger operable from the exterior of the casing and extending into the latter, means to cause step by step turning of the magazine by the movement of the trigger, and a firing device engageable by the magazine with the turning thereof to fire the gun.

2. A gun of the class described including a casing, having a discharge for the

cartridge, a trigger operable from the exterior of the casing and extending to the interior thereof, a revoluble magazine having radial cartridge chambers, a spring-pressed lever mounted to swing in a plane adjacent the magazine, a member on said lever adapted to be engaged by a cartridge chamber of the magazine in the turning of the latter by the trigger, a firing pin on said lever, and means to prevent retrograde movement of the magazine upon a firing movement of said lever.

3. A gun of the class described including a casing having a discharge for the cartridge, a trigger operable from the exterior of the casing and extending to the interior thereof, a revoluble magazine having radial cartridge chambers, a spring-pressed lever mounted to swing in a plane adjacent the magazine, a member on said lever adapted to be engaged by a cartridge chamber of the magazine in the turning of the latter by the trigger, a firing pin on said lever, means to prevent retrograde movement of the magazine upon a firing movement of said lever, and adapted to be engaged by the magazine when the latter is turned upon a turning movement of the latter by the trigger, a firing pin on said lever, and a spring stop adapted to be engaged by a cartridge chamber of the magazine in the movement of the latter by the trigger, said spring yielding to said movement of the magazine and adapted to spring into the path of said cartridge chamber after the latter has passed the spring.

JAMES FALLER.
ISAAC LAPIDUS.
